(57) **CLAIM**

The ornamental design for a laboratory instrument, as shown and described.

DESCRIPTION

FIG. 1 is a front perspective view of the laboratory instrument;

FIG. 2 is a rear perspective view of the FIG. 1 embodiment; FIG. 3 is a right side elevation view of the FIG. 1 embodiment, the left side elevation view being a mirror image thereof; FIG. 4 is a front elevation view of the FIG. 1 embodiment; FIG. 5 is a rear elevation view of the FIG. 1 embodiment; FIG. 6 is a top plan view of the FIG. 1 embodiment; and, FIG. 7 is a bottom plan view of the FIG. 1 embodiment. Broken lining shows features of the laboratory instrument that are not considered to be part of the design.

1 Claim, 7 Drawing Sheets
